BOILER WITH MULTIPLE SUPERHEATERS

George P. Jackson, Flushing, N. Y., assignor to
International Combustion Engineering Corporation,
New York, N. Y., a corporation of Delaware

Application May 1, 1931. Serial No. 534,269

3 Claims. (Cl. 122—480)

This invention relates to boilers with multiple superheaters and is particularly concerned with the type of boilers which are adapted to the burning of pulverized coal and in which relatively high superheat is desirable.

Generally considered, the invention has in view increased efficiency as well as flexibility of control with respect to the temperature and the like of the superheated steam.

10 The general nature of this invention, as well as the objects and advantages above-noted, and others which will occur to those skilled in the art, will be more apparent from the consideration of the following discussion making reference to 15 the accompanying drawings in which

Figure 1 is a vertical sectional view through a furnace-shaped boiler in which the present invention is embodied; and

20 Figure 2 is a vertical sectional view taken substantially as indicated by the section line 2—2 applied to Figure 1.

In Figure 1, it will be seen, the combustion space of the boiler is substantially defined, in its four vertical walls, by the tubes 3, these tubes, of 25 course, being subjected to radiant heat.

In accordance with the present invention, I have arranged or disposed superheater elements 4 in a portion of the furnace off-take 5 adjacent to the combustion space itself. These 30 superheater tubes 4 constitute the elements of a primary or first-stage superheater, and from inspection of Figure 2 it will be seen that these tubes are arranged in groups, the upper ones of which extend substantially throughout the entire cross sectional area of the off-take. Below 35 the groups just mentioned, additional tubes are arranged in groups which are spaced somewhat from each other at the center or mid-portion of the off-take and which extend to points adjacent 40 the off-take walls. In the space provided in this manner, I have arranged gas flow control means preferably comprising a duct 6 controlled by a damper 7.

In the upper portion of the furnace-shaped 45 boiler, most clearly illustrated in Figure 1, I have arranged a secondary or second-stage superheater comprising tubes 8. This superheater is preferably screened somewhat from the radiant heat of the combustion chamber as by means of 50 convection or water circulation tubes 9 extended from the steam and water drum 10 below the tubes 8 to the opposite side of the chamber. This secondary heater, it will be understood, is preferably arranged for serial connection with the 55 tubes 4 of the primary superheater, the relative

disposition of the two heaters being such as to afford very high delivered superheated steam temperatures. The reason for this, of course, is partly due to the multiple superheater arrangement, but results, more especially, from the fact that the secondary heater is disposed at a point in which gases of relatively high temperature contact therewith, as compared to the gases in the off-take.

Still further, the present invention includes a 65 re-heater 11 arranged in the off-take beyond the superheater tubes 4 with respect to the direction of gas flow therethrough. This re-heater 11, as appears most clearly in Figure 2, receives the gases after their passage through the tubes 4 as 70 well as through the by-pass or control duct 6.

At the low point 12 the off-take is doubled back to extend upwardly adjacent the first passage thereof, and in this upwardly extended off-take 75 passage I preferably arrange an air heater 13.

All of the foregoing features, it will be observed, are arranged in a very compact manner, the arrangement further being advantageous in affording maximum efficiency from the standpoint of heat losses from the installation, as by 80 convection or radiation. Additionally, the serial arrangement (speaking with reference to the contact of gases or products of combustion) of the secondary superheater, the primary superheater, re-heater, and an air heater, is generally 85 advantageous from the standpoint of utilization of gas temperature and specifically advantageous in effecting economies in an installation where relatively high superheat is desired. This arrangement, it might also be noted, provides for a 90 high superheat with a minimum of superheater elements or tubes disposed within the combustion chamber, i. e., in a very high temperature zone. In this way, replacements, repairs, or the like are considerably reduced in an installation 95 designed to produce superheat in the temperature ranges here contemplated. Still further, serial arrangement of the superheaters and the like, particularly in the manner herein disclosed, efficiently reduces gas temperatures to the desired 100 low point before exit.

Another important feature of this invention resides in the disposition of the by-pass or control means, for the gases passing through the superheater, in association with the tubes of the 105 first stage which are arranged in the off-take. The advantage of this arrangement will be more apparent if it is borne in mind that heretofore considerable difficulty has been encountered in 110 gas control where the by-pass elements have been

disposed in association with a superheater arranged in the combustion chamber itself. For example, in a construction such as illustrated in Figure 1, in which shielding tubes or screening elements are employed and disposed below the secondary superheater, accurate control for the gases passing over the tubes is very difficult to obtain if the control elements be associated with the tubes of this secondary heater. This will be apparent when it is considered that this secondary heater is disposed within the furnace-shaped boiler itself, which, of course, is of relatively large cross sectional area. In addition, the disposition of adjustable control means in association with a superheater arranged within the combustion chamber, at times produces uneven or irregular gas flow with respect to the superheater screening tubes.

In any case, I have found that much more accurate control may be obtained by the arrangement herein disclosed, i. e., an arrangement in which the control is afforded by the use of by-pass means associated with a primary superheater disposed in the off-take.

25 The operation of the by-pass duct, clearly illustrated in Figure 2, involves manipulation of the damper 7 either to provide substantially free and unobstructed flow through the duct (resulting in relatively small flow through the spaced groups of primary superheater tubes) or to materially restrict flow through the duct 6 and thus divert additional products through the tubes of the spaced groups. The damper 7, of course, may be controlled as by means of a thermostat associated with a superheater delivery line, preferably from the second stage, or, if desired, this damper 7 may be arranged for manual operation in accordance with various steaming and other operating or load conditions.

40 In accordance with the foregoing, uniform superheat is provided for under varying load and furnace operating conditions, it being apparent that in addition to this, the arrangement provides for maximum flexibility to meet varying 45 load or operating conditions which, at times, may require different degrees of superheat.

What I claim is:

1. In combination with a high temperature furnace-shaped boiler; an off-take at one side 50 thereof; a primary superheater in the off-take, said superheater including sets of tubes extended transversely of the direction of gas flow through the off-take and substantially the entire distance across the off-take from side to side there- 55 of whereby to provide for the passage therethrough of substantially all the gases flowing in the off-take, said superheater further including additional sets of tubes extended transversely of the direction of flow through the off-take, the 60 additional sets being disposed beyond the sets first mentioned with respect to the direction of gas flow and being spaced from each other; adjustable gas by-pass means in a space between the said additional sets of tubes; and a secondary 65 superheater extended across the top of the boiler.

2. In a high temperature boiler installation, 70 boiler tubes substantially wholly defining a combustion chamber to receive heat from the fuel and flame stream by radiation, an off-take from

said chamber, a primary superheater in an advance portion of the off-take, a secondary superheater disposed in the combustion chamber in a region thereof adjacent to the point of communication of said off-take, said primary and secondary superheaters being serially interconnected, in which construction, since the boiler tubes receive heat almost wholly by radiation and since steam flowing through the secondary superheater is at relatively high temperature, 80 the off-take gases passing over the primary superheater are also at relatively high temperature, the said primary superheater being divided into a plurality of sections serially arranged in the off-take, together with adjustable gas by-pass means in the off-take associated with a section of the primary superheater remote from the point of communication of the off-take with the combustion chamber, there being tubes of an advance section of the primary superheater disposed in gas-flow alignment with the gas by-pass means, whereby provision is made for the delivery of relatively highly superheated steam from said secondary superheater under temperature control by virtue of said by-pass without, 90 however, subjecting the adjustable by-pass means to excessive temperatures.

3. In a high temperature boiler installation; boiler tubes substantially wholly defining a combustion chamber to receive heat from the fuel and flame stream by radiation; an off-take from said chamber; a primary superheater in an advance portion of the off-take; a secondary superheater disposed in the combustion chamber in a region thereof adjacent to the point of communication of said off-take; said primary and secondary superheaters being serially interconnected; in which construction, since the boiler tubes receive heat almost wholly by radiation and since steam flowing through the secondary superheater is at relatively high temperature, 100 the off-take gases passing over the primary superheater are also at relatively high temperature; the said primary superheater being divided into a plurality of sections serially arranged in the off-take; adjustable gas by-pass means in the off-take associated with a section of the primary superheater remote from the point of communication of the off-take with the combustion chamber; there being tubes of an advance section of the primary superheater disposed in gas-flow alignment with the gas by-pass means, whereby provision is made for the delivery of relatively highly superheated steam from said secondary superheater under temperature control by virtue of said by-pass without, 110 however, subjecting the adjustable by-pass means to excessive temperatures; an air heater disposed in said off-take beyond said primary superheater; and a fluid carrying heat absorber in the off-take interposed 120 between the primary superheater and the air heater in gas-flow alignment with said gas by-pass means, whereby, even when the gas by-pass means is relatively widely opened, the gases passing through the by-pass means are reduced in 130 temperature before passage thereof through the air heater.

GEORGE P. JACKSON.
